(57) **CLAIM**

The ornamental design for a mat for sports, as shown and described.

DESCRIPTION

The patent or application file contains at least one drawing executed in color. Copies of this patent or patent application publication with color drawing(s) will be provided by the Office upon request and payment of the necessary fee.

2. Mat for sports

3. Mat for sports

Fig. 2.1 is a top plan view of the mat for sports;

Fig. 2.2 is a bottom plan view thereof;

Fig. 2.3 is a left-side elevation view thereof, the right-side elevation view being a mirror image thereof;

Fig. 2.4 is a front elevation view thereof, the rear elevation view being a mirror image thereof;

Fig. 3.1 is a top plan view of the mat for sports;

Fig. 3.2 is a bottom plan view thereof;

Fig. 3.3 is a left-side elevation view thereof, the right-side elevation view being a mirror image thereof; and

Fig. 3.4 is a front elevation view thereof, the rear elevation view being a mirror image thereof.

The dashed straight lines displayed on the mat form part of the claimed design. The dash-dot-dot-broken line circle portions and the dash-dot-dot-dash straight lines form no part of the claimed design. The color washed areas in Figs. 3.1-3.4 show portions of the design which form no part of the claim.
